UNITED STATES PATENT OFFICE.

FRED H. LINLEY, OF DULUTH, MINNESOTA.

COMBUSTION CONTROL IN STEAM-BOILER FURNACES.

Application filed October 5, 1926. Serial No. 139,672.

My invention relates to improved means for controlling combustion in furnaces and more particularly to a control means for maintaining a predetermined pressure in a combustion chamber by controlling the position of a damper, the damper being opened and closed automatically according to pressure conditions existing in the combustion chamber in a manner to exert a compensating influence for any differences occurring therein.

To this end, my improved control means comprises an electrical motor adapted for operation in either direction and connected to 15 open a damper when it is rotated in one direction and to close the damper when it is rotated in a reverse direction. This motor is provided with two electric circuits, each connected to effect a rotation of the motor in one 20 of the two directions and each containing a relay switch for connecting the motor through its particular circuit to a source of current. One or the other of the relays is connected to a source of current for operation by a control 25 switch which is movable according to pressure conditions found in the combustion chamber, this last named switch comprising a movable contact point positioned between and spaced from two stationary contact 30 points so that when the movable contact point is moved according to variances in pressure found in the combustion chamber, one or the other contact points is engaged to connect one or the other relays at the extreme 35 positions of movement of the movable contact point.

One of the objects of my invention is to provide a means for automatically maintaining the pressure in a combustion chamber of 40 a furnace substantially constant.

Another object of my invention is to provide a means for moving a damper used in connection with a combustion chamber of a furnace in accordance with the existence of 45 certain pressure conditions in the combustion chamber.

Another object of my invention is to provide a means for opening a damper used in connection with a combustion chamber of a furnace when the pressure in the combustion chamber reaches a certain predetermined maximum and for closing said damper when a pressure in the combustion chamber decreases below a certain predetermined 50 minimum.

Another object of my invention is to provide a motor for operating a damper of the above described type having two circuits, each for driving the motor in a different direction and means for connecting one or the other circuits of said motor to a source of current comprising a relay switch in each circuit and a selective switch for energizing one or the other of said relay switches, including two fixed contact points and a movable contact point, the movable contact point being positioned to engage one or the other of said fixed contact points at extreme positions of its movement, the movement of which is occasioned in accordance with the existence of varying conditions of pressure in the combustion chamber.

Another object of my invention is to provide a motor having two circuits of the type set forth in the above stated object and in 75 which each circuit is provided with a limit switch adapted to be thrown to open position in a manner to stop the motor after the motor has been run a predetermined amount.

Another object of my invention is to provide a manually operable switch for controlling a motor connected in a system of the above described type so that the automatic control means may be cut out and a manual 80 switch may be employed for connecting one or the other of the motor circuits so as to cause an opening or closing of the damper as desired by the operator.

These and other objects are accomplished by means of the arrangement disclosed on 90 the accompanying sheet of drawings, in which—

Figure 1 is a view of my control system partly in side elevation and partly diagrammatically represented. In this figure the 95 pressure responsive switch is disclosed showing the float and pipe connection leading to the combustion chamber, the remaining portion of the figure showing diagrammatically the electrical elements and connections;

Figure 2 is a plan view of the motor, reduction gearing and screw means for controlling the damper and for automatically throwing the limit switches; and

Figure 3 is a side elevation of the arrangement disclosed in Figure 2, this figure disclosing more fully the arrangement of the screw nut operating between the two limit switches.

The various novel features of the invention

will be apparent from the following description and drawings and will be particularly pointed out in the appended claims.

Referring to the drawings, it will be noted that my improved control device is adapted to be connected through the wall 10 of a combustion chamber by means of a pipe 11 having an upward extension 12 to serve as a mounting for the receptacle 13. Attached to the side wall of receptacle 13 are upstanding arms 14 supporting the cross beam 15 centrally bored as at 16 to receive in slidable relation the rod of insulating material 17. Mounted on the lower end of the rod 17 is a bell shaped float element 18 positioned in the receptacle 13 and over the upper end of the pipe 12 so that when the receptacle 13 is partially filled with a liquid such as oil to make a seal, the bell member 18 forms a float adapted to move up and down according to varying pressure conditions communicated to the interior of the bell 18 through pipes 11 and 12. Mounted on the underside of the cross beam 15 to one side of the center thereof is the insulating block 19 forming a support for the contact elements 20 and 21. Positioned between the contact elements and mounted rigidly on the rod 17 is a disk 22 adapted to form with the contact elements 20 and 21 a double switch mechanism operating when the bell float is in extreme upward position to connect one circuit of my system and when in extreme lower position to connect a second circuit of my system. The contact disk 22 is connected by the wire 23 having a resistance element 24 connected therein to one terminal of a source of current designated generally as A. Each of the other contact points 20 and 21 is connected by means of wires 25 and 26 respectively to a relay designated generally 27 and 28 and from thence by wire 29, switch 30, and wire 31 to the other terminal of the source of current designated generally as B. An electrical motor adapted for rotation in either direction is designated generally as C and is provided with a rotor 32 and the split series coil 33 and 34, each connected in a separate circuit to terminal B of the source of current by relay switches 27 and 28. In each of the circuits just mentioned is a limit switch 35 and 36 adapted to cut off the source of current in the particular circuit of each, the purpose and operation of which will be hereinafter described.

The first of the two circuits for connecting the motor for operation comprises the rotor 32 connected at one end of the terminal of the source of current A, coil 33, switch 35, wire 37, terminals 38 on the relay 27, wire 39, switch 30 and wire 31 completing the circuit back to the terminal B of the source of current. The second circuit for connecting the motor comprises the rotor 32, coil 34, switch 36, wire 40, terminal 41 on the relay 28, wires 42 and 29, switch 30 and wire 31. Extend-

ing across these two circuits in a manner to cut out the relays of the automatic control mechanism are the two wires 43 and 44 having the switch 45 connected intermediate their lengths in a manner to permit a connection of the motor through either one of the circuits selectively to the source of current by a manual control so that the damper may be controlled independently of the automatic means. The switch 45 is provided with a movable switch arm 46 effective to connect either one of the circuits when the arm 47 of the switch 30 is positioned to engage the contact 48.

Referring to Figures 2 and 3, the operating means for the damper comprises a motor designated generally as C adapted to drive through a coupling 49, a series of reduction gears housed in a casing 50 so as to rotate the shaft 60 extending out of the housing at a 90° angle to the axis of the motor. Positioned in the other end of the shaft 60 in a socket 61 is the finely threaded rod 62 held in the socket by the pin 63 and having threaded thereon a nut member 64. The outer end of the rod 62 is provided with sleeves 65 connected by the pin 66 forming a connection for the second screw threaded shaft 67 held in the other end of the sleeve 65 by the pin 68. Mounted on this shaft, the threads of which are coarser than those on shaft 60, is the nut member 69 fixed in the outer end of the pipe 70 so as to move the pipe longitudinally upon rotation of the shaft, the pipe 70 being connected to operate through suitable mechanical connections the damper of the combustion chamber. Depending from the nut 64 is an arm 71 positioned to slide in a groove 72 provided on the upper side of an electrical switch mechanism designated generally as 73. The switch 73 is provided with two pivots shown at 74 on which are mounted two contact arms 75 and 76 held normally by the spring 77 to engage the contact points 77 and 78 respectively. The upper ends of the arms are extended to a position to be engaged by the lower end of the depending arm 71 of the nut 64 in such a manner that the nut 64 will engage one or the other of these arms at its extreme opposite positions of movement. The nut 64 is supplied with a grease cup 79, adapted to keep the threaded surface between the nut and the rod well lubricated. It is to be understood that the switch mechanism shown in Figure 120 comprising the contacts 77 and 78 and the lever arms 75 and 76 are the same switches designated generally as 35 and 36 in Figure 1.

In operation it will be found that an unusually high pressure existing in the combustion chamber may be partially reduced by opening the damper employed in connection with the combustion chamber. Upon the existence of such an extreme pressure, the bell 130

float member 18 is forced upwardly under the action of the increased pressure communicated to its interior to an extent causing the contact elements 22 to engage the contact point 20. When the parts are in this position, the coil of the relay designated generally as 27 is energized provided the switch arm 47 of switch 30 is in contact with the point 48 and being so energized causes the contact closing arm 38' to be moved to close the gap between the contact points 38. In this case, the coil 33 of the motor is energized and the motor set into operation thereby in a direction to cause the damper to be opened. The motor having been set in operation as described will cause rotation of the rod 62 and 67 as shown in Figures 2 and 3. The rotation of the rod 67 causes the nut 69 to move the pipe 70 in a manner to open the damper and at the same time the nut 64 is forced to travel along the rod 62 so as to engage the switch arm 76, the switch arm 76 being that which is represented at 35 in Figure 1. From this arrangement it may be readily understood that after 25 the float 18 has acted, through the instrumentality of one or the other of the two relays to connect the motor for operation through one or the other of its circuits, the motor will run until contact is broken between contacts 20 and 22. This breaking of contacts is caused by the lowering of the bell float member 18 due to the reduction of pressure in the combustion chamber effected by the closing of the damper. In case the closing of the damper did not cause the necessary reduction of pressure, the motor would continue to run until the particular circuit connection effecting the operation would be disconnected by the moving arm 71 traveling 40 along the rod 62, thereby disengaging the particular switch arm 75 or 76. From this explanation it is apparent that when the pressure in the combustion chamber is diminished, a circuit is formed by the contact points 22 and 21 to operate the relay 28 and switch arm 41' to establish a circuit to operate the motor in the reverse direction, the principle involved, however, in the above instances being the same. By movement of 45 the switch arm 47 of the switch 30 over to the point 48, the automatic control means may be entirely cut out and the motor operated in a direction to either open the damper or to close the damper at the will of the operator merely 50 by manipulating the control switch designated generally 25.

I claim:

1. In combustion control mechanism, means for operating a damper comprising a motor having two circuits, one for each direction of rotation, each circuit being adapted to be connected to a source of current by a relay, means for operating one or the other of said relays depending upon pressure conditions in a combustion chamber, comprising
2. In combustion control mechanism, a double switch mechanism having two fixed contact points and a movable contact point, the movable contact point and one of said two contact points being connected when the pressure in said combustion chamber increases a certain predetermined extent and the movable contact point and the other of said two contact points being connected when said pressure in said combustion chamber diminishes to a certain predetermined extent.
3. In a device of the character described means for varying the pressure in a combustion chamber and control mechanism comprising a reversible motor, two field circuits for said motor, each of said circuits being normally opened, a relay for closing each of said circuits, each of said relays being connected in independent normally opened circuits, and means for selectively closing one or the other of said relay circuits according to pressure conditions in a combustion chamber.
4. In a device of the character described means for varying the pressure in a combustion chamber and control mechanism comprising a reversible motor, two field circuits for said motor, each of said circuits being normally opened, a relay for closing each of said circuits, each of said relays being connected in independent normally opened circuits, and means for selectively closing one or the other of said relay circuits according to pressure conditions in a combustion chamber, and switch means for cutting out said relays and a manual switch for selectively closing one or the other of said two field circuits.
5. In a device of the character described means for varying pressure in a combustion chamber, control mechanism therefor comprising a reversible motor, two field circuits for said motor, each of said circuits being normally opened, a relay for closing each of said circuits, each of said relays being connected in independent normally opened circuits, and a double acting switch for closing one of said relay circuits when the pressure in a combustion chamber reaches a certain predetermined maximum, and for connecting the other of said relay circuits when the pressure in said combustion chamber reaches a certain predetermined minimum.
6. In a device of the character described means for varying the pressure in a combustion chamber, control mechanism therefor comprising a reversible motor, two field circuits for said motor, each of said circuits being normally opened, a relay for closing each of said circuits, each of said relays being connected in independent normally opened circuits, and a double acting switch for closing one of said relay circuits when the pressure in a combustion chamber reaches a certain predetermined maximum, and for connecting the other of said relay circuits when the pressure in said combustion chamber reaches a certain predetermined minimum.

- tion chamber and control mechanism comprising a reversible motor, two field circuits for said motor, each of said circuits being normally opened, a relay for closing each of 5 said circuits, each of said relays being connected in independent normally opened circuits, and means for selectively closing one or the other of said relay circuits according to pressure conditions in a combustion chamber, said means comprising a pair of spaced, fixed terminals and a movable terminal carried by a pressure responsive element, and normally out of contact with said pair of spaced terminals, but adapted to contact one 10 or the other of said spaced terminals upon predetermined movement in either direction.
7. In a device of the character described means for varying the pressure in a com-

bustion chamber and control mechanism comprising a reversible motor, two field circuits for said motor, each of said circuits being normally opened, a relay for closing each of said circuits, each of said relays being connected in independent normally opened circuits, and means for selectively closing one or the other of said relay circuits according to pressure conditions in a combustion chamber, each of said two field circuits having a normally closed limit switch adapted to be opened by said motor when in operation after a predetermined number of revolutions thereof.

Signed at Duluth, Minnesota, this 24th day of September, 1926.

FRED H. LINLEY.
